(57) CLAIM

I claim the ornamental design for an ornamental bar, as shown and described.

DESCRIPTION

FIG. 1 is a front isometric view of an ornamental bar showing my new design;

FIG. 2 is a front view thereof;

FIG. 3 is a back view thereof;

FIG. 4 is a right side view thereof;

FIG. 5 is a left side view thereof;

FIG. 6 is a top view, the opposite view being a mirror image;

FIG. 7 is an enlarged back view thereof;

FIG. 8 is an enlarged front view thereof;

FIG. 9 is an enlarged top view thereof; and,

FIG. 10 is an enlarged left side view thereof.

A bottom view has been omitted as it is merely a mirror image of the top view.

An enlarged right side view has been omitted as it is merely a mirror image of the enlarged left side view.

The broken lines depicting portions of the ornamental bar in the drawing are for illustrative purposes only and form no part of the claimed design.
